RAILWAY TRAFFIC CONTROLLING
APPARATUS

Henry S. Young, Wilkinsburg, Pa., assignor to
The Union Switch & Signal Company, Swiss-
vale, Pa., a corporation of Pennsylvania

Application September 25, 1931, Serial No. 565,936

12 Claims. (Cl. 246—134)

My invention relates to railway traffic controlling apparatus, and particularly to apparatus for governing traffic at points where two or more tracks intersect or converge.

5 I will describe one form of my invention, and will then point out the novel features thereof in claims.

The accompanying drawings, Figs. 1 and 2 when placed together with Fig. 1 on the left, constitute a diagrammatic view showing one form of my invention when applied to a layout wherein two tracks cross each other, and a third and fourth track branch from the intersecting tracks.

Referring to Figs. 1 and 2, the reference characters *a* and *b* designate the tracks of two railroads that intersect at the point 25. The reference character *c* designates a siding or transfer track branching from the track *b*, while *d* is a passing siding for the track *a*. The track *a* is divided 10 by the usual insulated rail joints 10 into track sections A1T, 1T and A3T of which A1T and A3T may be termed approach sections and 1T a crossing track section. The track *b* is divided in a similar manner into the track sections A4T, 4T, 15 B5T and A5T of which 4T is a crossing track section and A5T, B5T and A4T are approach track sections. The traffic rails of the sections 1T and 4T at the crossing 25 are insulated from each other by the usual insulated joints and are made 20 electrically continuous by conductors around the insulated joints in the customary manner as will be readily observed by an inspection of Fig. 2. The track section B5T is preferably made only 25 a few rails in length, say one hundred feet.

30 Each track section of the tracks *a* and *b* is provided with the conventional track circuit consisting of a source of current such as a battery connected across the traffic rails adjacent one end of the section. Connected across the traffic rails 35 adjacent the opposite end is a track relay designated by the reference character *R* plus a prefix corresponding to the track section. It will thus be seen that each track section is equipped with a track circuit that includes a track battery 11,

40 a track relay *R* and the traffic rails of the section in series. A track repeater relay A5TP is controlled by a circuit that includes the front contacts of the armatures 103 and 106 of the track relay B5TR and the front contacts of the armatures 104 and 105 of the track relay A5TR as will 45 be readily understood by an inspection of Fig. 2.

50 Energy for operating the apparatus of my invention may be obtained from any convenient source either alternating current or direct current but which is not shown in the figures. For

this description I shall consider the source to be direct current and that the relays are direct current relays. Throughout the figures the positive terminal of the source of current is designated by the reference character BL and the negative terminal by the reference character CL.

Traffic from the left to the right over the track *a* I shall term eastbound traffic, and traffic from the right to the left over track *a* I shall term westbound traffic. Traffic moving from the left 60 to the right on the track *b* I shall term northbound while traffic in the opposite direction on the track *b* will be spoken of as southbound. While the siding *d* and the transfer track *c* are shown in the figures as branching from the track 65 sections 1T and A5T, respectively, it will be understood that these siding tracks may extend from other track sections, and also that there may be additional sidings without departing from the spirit and scope of my invention. The track layout 70 illustrated in Figs. 1 and 2 will serve to illustrate the principle of my invention.

In order to simplify the figures, so that they may be more readily understood, I shall show at 75 different points in the figures certain of the armatures for the different relays at locations not adjacent to the relay. In each instance this armature will be given a reference character corresponding to the relay that operates that armature plus a distinguishing exponent and the 80 armature will be shown in the position corresponding to the normal condition of the relay. For example, in Fig. 1 the armature designated by the reference character A3TR¹² is operated by the track relay A3TR of Fig. 2 and the armature 85 is shown in engagement with its front contact inasmuch as the relay A3TR is normally energized. The switch A1 leading to the passing siding *d* has connected to it a circuit controller L as is indicated by a dotted line. In accordance 90 with standard practice this circuit controller is operated between its two circuit controlling positions in step with the switch A1 as it is set for the track *a* or for the siding *d*. At certain points in the drawings there are shown contacts of the 95 controller L which are designated by the reference character L plus a distinguishing exponent. These contacts are shown in the position that corresponds to the position occupied by the controller L when the switch A1 is set for the track *a*.

100 Eastbound traffic on the track *a* is governed by the wayside signals 1 and 6, and westbound traffic by the signals 3 and 7. Northbound traffic on track *b* is governed by the signals 4 and 8, while the southbound traffic is governed by signals 105 110

5 and 9. The signal 2 governs eastbound traffic moving from the siding *d*. Signal 5 is provided with two mechanisms A and B. Signal A5 governs through southbound traffic while signal B5 is a 5 special slow speed signal to govern a train that has stopped to do switching in the vicinity of the transfer track *c* as will be more fully explained hereinafter. These wayside signals may 10 be of any standard type in general use and are here indicated by symbols only. The signals 6, 15 7, 8 and 9 act as distant signals for the associated signals 1, 3, 4 and 5, respectively, and as these distant signals form no part of my invention the means for their control is omitted from the figures and these signals will not be further referred to. The signals 1, 2, 3, 4 and 5 each 20 govern traffic over the crossing 25 and each is capable of assuming either a clear or a stop indication. As the operating circuits for these wayside signals form no part of my invention, they are omitted from the figures for the sake of clearness. It will be understood that the operating circuits for each signal are governed by a signal controlling relay, to be shortly pointed out, in 25 such a manner that when the relay is energized the signal is cleared, while as long as the relay is deenergized the corresponding signal is set at stop.

The signal controlling relays governing the operation of the signals are designated by the reference character H plus a prefix corresponding to the signal. The controlling circuit for the signal controlling relay 1H, that governs the operation of signal 1, starts at positive terminal BL 30 and includes the front contact of armature 14 of the track relay 1TR for track section 1T, front contact of armature 15 of track relay 4TR for section 4T, wire 16, normally closed contact 17 of a manually controlled time release *b*⁴ to be referred to later, normally closed contact 18 of a second manually controlled time release *a*³, front contact of armature 19 of a route locking relay 4—5LS associated with north and southbound traffic as will be described later, wire 20, contact L²¹ of the switch circuit controller L, back contact of armature 22 of the signal controlling relay 2H, back contact of armature 3S²² of a stick relay 3S associated with signal 3 and to be described later, back contact of armature 3H²⁴ of the signal controlling relay 3H, front contact of armature A3TR²⁶ of the track relay A3TR, back contact of armature 27 of track relay A1TR for the approach track section A1T, winding of relay 1H and to the negative terminal CL. As 35 this circuit is normally open at the back contact of armature 27 of the track relay A1TR for the approach track section A1T, it follows that under normal conditions an eastbound train upon entering the approach section A1T and shunting the track relay A1TR will cause the signal 1 to be cleared. It is also to be noted that the circuit for relay 1H is held open at armature 3H²⁴ whenever the signal controlling relay for the opposing signal 3 is energized to clear its signal, 40 also, when either crossing track section 1T or 4T is shunted, or when the route locking relay 4—5LS is deenergized so that armature 19 is down.

The relay 2H that governs the operation of the signal 2 is controlled by the same circuit above traced for the relay 1H from positive terminal BL up to the contact L²¹ of the switch circuit controller L, hence, when the switch A1 is set for the siding *d* and the contact L²¹ moved to its lower position as shown in Fig. 1, the circuit

extends along wire 28, back contact of armature 29 of relay 1H, back contact of armature 3H³⁰ of relay 3H, front contact of armature A3TR³¹ of the track relay A3TR, winding of relay 2H and to the negative terminal CL. It follows 80 that whenever the switch A1 is reversed for a traffic movement from the siding *d* the relay 2H is energized and the signal 2 is cleared if the remaining apparatus occupies its normal position. It is to be noted especially that the relay 2H 85 cannot be picked up if either of the crossing track sections 1T or 4T are occupied, or if the route locking relay 4—5LS is deenergized.

The relay 3H that governs the westbound signal 90 3 has a circuit that starts at positive terminal BL and extends along the same circuit as traced for the relay 1H up to the back contact of armature 22 of relay 2H, thence by wire 32, back contact of armature 1S³³ of a stick relay 1S associated with signal 1 as will be described later, back contact 1H³⁴ of relay 1H, front contact of armature A1TR³⁵ of the track relay A1TR, back contact of armature 36 of track relay A3TR for the approach track section A3T, winding of relay 3H and to the negative terminal CL. As this circuit is normally 100 completed except at the back contact of armature 36 of relay A3TR, it follows that under normal conditions a westbound train entering the approach track section A3T will cause relay 3H to become energized to clear the signal 3. It will be 105 noted in connection with this circuit for the relay 3H that it is held open whenever a signal controlling relay for the opposing signals 1 or 2 is energized. Also that the circuit is controlled by the crossing track sections 1T and 4T and by the 110 route locking relay 4—5LS.

The circuit to the signal controlling relay 4H governing the operation of the signal 4 is the same as that traced for the relay 1H from positive terminal BL up to the wire 16, hence by a 115 110 normally closed contact 37 of the time release *b*⁴, normally closed contact 38 of the time release *a*³, back contact of armature 39 of relay 3H, wire 40, back contact of armature 41 of relay 2H, back contact of armature 42 of relay 1H, front contact 120 of armature 43 of a route locking relay 1—3LS associated with east and westbound traffic as will be described later, a back contact 44 and a checking contact 45 of a time element device 5TE to be described later, back contact of armature 5S⁴⁶ of 125 a stick relay 5S associated with signal 5, back contact of armature B5H⁴⁷, back contact of armature A5H⁴⁸, front contact of armature A5TP⁴⁹, back contact of armature 50 of track relay A4TR for the approach track section A4T, winding of 130 relay 4H and to the negative terminal CL. As this circuit is normally completed except at the back contact of armature 50 of the track relay for the approach track section A4T, it is to be seen that under normal conditions a northbound 135 train upon entering the approach track section A4T will cause the relay 4H to be energized and the signal 4 cleared. In connection with this circuit for the relay 4H it is to be noted that the circuit will be opened when a signal controlling 140 relay for the opposing signal 5 or for one of the signals 1, 2 or 3 of the crossing road is energized, and that it is controlled by the track sections 1T and 4T, and by the route locking relay 1—3LS 145 associated with east and westbound traffic.

The relay A5H that governs the operation of the mechanism A of signal 5 is controlled by the same circuit just traced for relay 4H up to the armature 43 of the route locking relay 1—3LS, thence by the wire 51, back contact of armature 150

4S⁵² of a stick relay 4S associated with signal 4, back contact of armature 4H⁵³ of relay 4H, front contact of armature A4TR⁵⁴, back contact of armature A5TP⁵⁵ of the track repeater relay A5TP governed by the approach track section A5T, back contact 5TE⁵⁶ of the time element device 5TE, winding of relay A5H and to the negative terminal CL. As this circuit is normally completed except at the back contact of armature A5TP⁵⁵, it follows that when a southbound train enters the approach track section A5T, relay A5H will be energized to clear the signal A5. The circuit for this relay A5H is opened if the signal controlling relay for the opposing signal 4 or if the controlling relay for one of the signals 1, 2 or 3 of the crossing road is energized, and it is controlled by the track sections 1T and 4T and by the route locking relay 1—3LS.

The relay B5H that governs the special low speed signal B5 is provided with a circuit that is the same as that described for the relay A5H from positive terminal BL up to the armature A5TP⁵⁵ of the track repeater relay A5TP from which point there extends a circuit network of parallel paths to the winding of the relay B5H. All paths of this network extend from the armature A5TP⁵⁵ through the front contact of armature 5TE⁵⁷ of the time element device 5TE from which point one path includes contact L⁵⁸ of the switch circuit controller L, front contact of armature A3TR⁵⁹, front contact of armature A1TR⁶⁰, winding of relay B5H and to the negative terminal CL. Another path includes the back contact of armature B5TR⁶¹ and to the winding of the relay B5H. From contact L⁵⁸ there is one path that includes the front contact of armature 1S⁶² of the stick relay 1S and the armature A1TR⁶⁰, and a second path that includes the armature A3TR⁵⁹ and the front contact of armature 3S⁶³ of the stick relay 3S. As the circuit for the relay B5H is the same as that for the relay A5H up to the circuit network this relay B5H can be energized under normal conditions only when a southbound train occupies the section A5T. As each path of the circuit network leading to the relay B5H includes the front contact of the armature 5TE⁵⁷, it follows that for the relay B5H to be energized to clear the special signal B5 a sufficient time must elapse for the time element device 5TE to function. The operation of the time element device 5TE and of the circuit network for the relay B5H will be more fully pointed out when the operation of the system is described for southbound traffic.

From the description of the circuits for the signal controlling relays, it follows that as a train approaches the crossing 25 on any track a signal controlling relay becomes energized to clear a signal for that train to advance over the crossing. As this signal controlling relay picks up it opens at back contacts the controlling circuit for the signal controlling relay of the opposing signal. It is to be noted, however, that the circuits for the signal controlling relays 4H, A5H and B5H for the north and south road include back contacts of armatures 42, 41 and 39 of the relays 1H, 2H and 3H for the east and west road, respectively, while similar back contacts are not included in the circuits leading to the relays 1H, 2H and 3H. This gives a slight advantage to the relays for the east and west road in the case of trains on each of the crossing roads entering an approach section simultaneously.

For each signal there is provided a stick relay designated by the reference character S with a

prefix corresponding to the signal. As the circuit for each of the stick relays is substantially the same it is thought that a detailed description of one will be sufficient for an understanding of all. Referring to the stick relay 3S associated with signal 3 we find that this relay has an energizing circuit that extends from the positive terminal BL through a back contact of armature 1TR⁶⁴ of the track relay 1TR, front contact of armature 65 of the relay 3H when that relay is energized to clear signal 3, winding of the relay 3S and to the negative terminal CL. Once relay 3S is energized it is held energized by a stick circuit from armature 1TR⁶⁴ through a front contact of its own armature 66, or by a second stick circuit that extends from positive terminal BL through the back contact of armature A1TR⁶⁷ of the track relay A1TR, back contact of armature 65 and the front contact of its own armature 66. From the foregoing we see that the stick relay 3S is picked up during the interval that the relay 3H remains up after a train shunts the track relay 1TR as it passes the signal 3 when the signal controlling relay 3H is energized. The signal controlling relay 3H, as all signal controlling relays of my system, is provided with slow-releasing characteristics that will retain its armature in engagement with its front contacts for a period sufficiently long to permit the stick relay 3S to be picked up after the track relay 1TR has been shunted. With this stick relay 3S once picked up it is retained energized by its stick circuits that are held closed as the westbound train travels through the track sections 1T and then moves away from the crossing through the opposing approach track section A1T.

The stick relay 1S associated with the signals 1 and 2 has an energizing circuit similar to that described for relay 3S, and then in addition there is provided a second energizing circuit that includes the back contact of armature 167 of the track relay 1TR, back contact of armature 68 of relay 1H and the front contact of the armature 69 of the relay 2H. Thus this relay 1S becomes energized when a train moves east from the siding d into the track section 1T as well as when an eastbound train advances on the track a past the signal 1 into section 1T. The stick circuits for the relay 1S are substantially similar to those described for the relay 3S, one including the back contact of armature 167 and the other the back contact of A3TR⁷⁰, and thus the relay 1S is retained energized while an eastbound train occupies the section 1T and also while it moves away from the crossing 25 through the opposing approach track section A3T. The circuits for the stick relay 4S associated with the signal 4 are similar to those described for the relay 3S and will not be further referred to. Stick relay 5S associated with the signal 5 has two energizing circuits, one extends from positive terminal BL through the back contact of armature 4TR⁷¹, front contact of armature 72 of relay A5H and the winding of relay 5S to negative terminal CL. The second energizing circuit includes the back contact of armature 72, the front contact of armature 73 of relay B5H, and to the winding of relay 5S. Thus the stick relay 5S will be energized when a southbound train advances past signal 5 with either relay A5H or B5H energized. The stick circuits for relay 5S are similar to those for relay 3S. One circuit includes the back contact of armature 4TR⁷¹, and the second includes the back contact of armature A4TR⁷⁴ of the relay A4TR. It follows that each stick relay will be

picked up as a train advances past the associated signal in a clear position and will be retained energized until that train has passed over the crossing and has vacated the opposing approach track section. The function of each stick relay will be pointed out when the operation of a system is discussed.

There is provided for each road a route locking circuit and relay. The route locking relay 4-5LS is associated with the east and westbound traffic while the route locking relay 1-3LS is associated with the north and southbound traffic. Referring to the relay 1-3LS, this relay is normally energized by a route locking circuit that starts at the positive terminal BL at the back contact of armature 75 of relay 1H and includes the back contact of armature 76 of relay 2H, back contact of armature 3H⁷⁷, wire 78, contact L¹³ of the switch circuit controller L, front contact of armature A1TR⁷⁹, front contact of armature 1TR⁸⁰, front contact of armature A3TR¹², winding of the relay 1-3LS and to the negative terminal CL. From the wire 78 there branches a normally closed stick circuit through the front contact of the armature 81. From wire 78 there also branches two normally open parallel pick-up circuits. One pick-up circuit is through the front contact of armature 1S⁸² and the back contact of armature A3TR¹² to the winding of the relay 1-3LS. The second pick-up circuit extends from wire 78 along wire 83, normally open contact 84 of the time release a³ and wire 85 to the winding of the relay 1-3LS. Still another pick-up circuit for this relay branches from the contact L¹³ through the normally open back contact of armature A1TR⁸⁶ for the track relay A1TR, normally open front contact of armature 3S⁸⁷ of stick relay 3S and to the winding of the relay 1-3LS. Except to point out that the relay 1-3LS is retained energized by its stick circuit as long as the three signal controlling relays 1H, 2H and 3H are deenergized, the function of this network of circuits associated with the relay 1-3LS will not be taken up in detail until the operation of the system is described.

The route locking relay 4-5LS associated with north and southbound traffic is provided with a circuit network substantially similar to that described for the relay 1-3LS. The relay 4-5LS is normally energized by a circuit that starts at the positive terminal BL at the armature 88 of relay B5H and includes the back contact of armature 89 of relay A5H, back contact of armature 4H⁹⁰ of the relay 4H, wire 91, front contact of armature A4TR⁹², front contact of armature 4TR⁹³, front contact of armature A5TP⁹⁴, winding of relay 4-5LS and to the negative terminal CL. From the wire 91 there branches a stick circuit through the front contact of its own armature 95. Three parallel paths also branch from the wire 91 to the winding of the relay 4-5LS by the means of which this relay can be energized. One path includes the front contact 96 of the time release b⁴, a second path includes front contact of the armature 4S⁹⁷ and the back contact of armature A5TP⁹⁴, while a third path includes back contact of armature A4TR⁹⁸ and the front contact of armature 5S⁹⁹. The function of this network of circuits will be pointed out when the operation of the system is considered. In addition to this network of circuits just traced for the relay 4-5LS there is also provided a pick-up circuit that extends from positive terminal BL the same as above described up to the wire 91 and then through a front contact of the armature 107 of

the time element relay 5TE and wire 108 to the winding of the relay 4-5LS. Furthermore, the relay 4-5LS may be picked up over the back contact of the armature 1-3LS³ of the opposing route locking relay 1-3LS. This last circuit permits the route locking relay 4-5LS to be picked up and release the signal controlling circuits to the track a in the event there occurs a simultaneous deenergizing of both route locking relays due to a train on each of the crossing roads entering an approach track section simultaneously. This feature, together with the above-mentioned fact that the circuit for the signal controlling relays of the north and south road is controlled by back contacts of the signal controlling relays of the east and west road, give precedence to the east and westbound trains over north and southbound trains when trains on each road enter an approach track section simultaneously.

Associated with the tracks b and c is a time element device or relay 5TE. This time element device may take different forms several of which are well-known in the art, but a preferred form is that of a time element relay wherein circuit contacts are not operated until a predetermined time interval after the energizing circuit for the winding of the relay has been closed. The time element device 5TE is provided with a circuit that starts at the positive terminal BL at the normally open back contact of the armature 100 of the relay A5TP, and includes wire 101, back contact of armature 102 of the 4S stick relay, winding of the relay 5TE and to the negative terminal CL. Thus, when a southbound train occupies either track section A5T or B5T, the circuit to the time element relay 5TE is closed and after a predetermined time interval, which I shall speak of as being five minutes, the armatures 107 and 5TE⁵⁷ are brought into engagement with front contacts while the armatures 44 and 5TE⁵⁶ are lifted out of engagement with their back contacts. When this energizing circuit to the winding of relay 5TE is ruptured, the armatures immediately return to their normal position.

In describing the operation of the system I shall first assume an eastbound train enters the approach track section A1T at a time when all the other track sections are unoccupied. As the track relay A1TR is shunted the circuit to the relay 1H is closed and that relay is energized to clear the signal 1. As soon as the relay 1H is energized the circuits to the signal controlling relays for the opposing signals 2 and 3 and to each controlling relay of the signals of the crossing road are opened to prevent any of these signals from clearing. As the track relay A1TR is shunted the circuit to the route locking relay 1-3LS is opened at the armature A1TR⁷⁹ and then as soon as relay 1H picks up the stick circuit of relay 1-3LS is opened at the armature 75 and this route locking relay is deenergized to lock out the signal controlling relays for the north and south road at the armature 43. As the eastbound train advances past the signal 1 into the section 1T and shunts the track relay 1TR, the circuit to the relay 1H is opened at the armature 14 and at the end of its slow-release period signal 1 is set at stop. As the train shunts the track relay 1TR the energizing circuit for the stick relay 1S is closed during the release period of the relay 1H. After relay 1S is once picked up it is retained energized by its stick circuits as long as the eastbound train occupies either track section 1T or A3T. As the relay 1H becomes deenergized when the track relay 1TR is shunted it closes the normal ener-

gizing circuit to the relay 1-3LS at the back contact of the armature 75, but this circuit to the route locking relay is held open at the front contact of armature 1TR⁸⁰ of the track relay 1TR or 5 at the front contact of the armature A3TR¹² of the track relay A3TR as long as the eastbound train occupies the track sections 1T and A3T, respectively.

As previously pointed out there is provided an 10 energizing circuit to the relay 1-3LS that includes the front contact of the armature 1S⁸² of the stick relay 1S and the back contact of the armature A3TR¹² of the track relay A3TR. The energizing of the stick relay 1S is accomplished 15 as the eastbound train entered the section 1T and then as the eastbound train enters the section A3T and shunts the track relay A3TR the stick relay 1S is retained energized and thus this energizing circuit through armatures 1S⁸² 20 and A3TR¹² to the relay 1-3LS is completed and the relay is picked up. That is to say, to energize the route locking relay 1-3LS requires two steps, the first of which is accomplished as the eastbound train entered the section 1T and 25 picked up the stick relay 1S. The second step is accomplished as the train subsequently enters the track section A3TR. With relay 1-3LS energized a signal for the crossing road can be cleared as soon as the eastbound train vacates 30 the section 1T and the track relay 1TR becomes energized to close the front contact of the armature 14.

As noted above the stick relay 1S is held energized through the back contact of the armature A3TR⁷⁰ and as the control for the 3H relay for the signal 3 includes the back contact of armature 1S⁸³ it is apparent that this signal 3 will not be cleared by the eastbound train entering the section A3T although as the track 40 relay A3TR is shunted it closes the back contact of armature 36. The stick relay 1S, therefore, serves two functions, first, to complete the first step in the energizing of the route locking relay 1-3LS, and second, to prevent the clearing of 45 the westbound signal 3 when an eastbound train occupies the approach track section A3T.

As the eastbound train vacates the section A3T the second stick circuit for the relay 1S is opened and that relay deenergized. As relay A3TR 50 picks up, the normal circuit for the relay 1-3LS is closed and thus the apparatus is restored to its normal position. Furthermore, it is to be noted that should an eastbound train enter the approach section A1T and then back out of that section the relay 1H will first be picked up to clear the signal 1 and the route locking will become effective in the manner previously described, but as soon as the train backs out of the section the signal controlling relay 1H will 60 become deenergized so that the signal 1 is restored to its stop position and the route locking is restored to its normal condition.

If, while the eastbound train occupied the approach track section A1T the section A3T should be momentarily shunted, the deenergizing of the track relay A3TR will deenergize the relay 1H and the signal 1 is set at stop, but the stick relay 1S will not become energized and thus the route locking relay 1-3LS will not be reenergized. As 65 the front contact of armature 43 is in the control of all signals of the crossing road, the momentary shunting of the section A3T with an eastbound train approaching the signal 1, will not make it possible for a signal on the other road to be cleared. It will be further observed

that a momentary shunting of the section 1T will not permit the clearing of a signal on the crossing road while the eastbound train is approaching the signal 1. The shunting of the track relay 1TR will result in the stick relay 1S becoming energized and thus close the front contact of armature 1S⁸² in the pick-up circuit of the relay 1-3LS. This pick-up circuit is, however, still held open at the back contact of armature A3TR¹² of the track relay for the section A3T. If the shunt on the section 1T is but momentary then as soon as it is removed the relay 1H will again pick up to clear the signal 1 and to deenergize the stick relay 1S. It is to be seen, therefore, that the two subsequent steps required for the release of the route locking insures that a momentary or premature shunting of the track sections in advance of the train will not result in a condition that will permit the clearing of a signal for the crossing road.

The operation of the apparatus for a westbound train is similar to that described for an eastbound train. The westbound train upon entering the approach section A3T closes the circuit to the relay 3H to clear the signal 3 and to open 100 the circuit for the relay 1-3LS at the back contact of the armature 3H⁷⁷. Stick relay 3S is picked up as the train enters the section 1T and is held energized by its stick circuits as long as the westbound train occupies either track section 105 1T or A1T. The route locking relay 1-3LS is reenergized in two steps, the first being accomplished as the stick relay 3S is picked up to close the front contact of armature 3S⁷⁷, and the second step is accomplished when the track relay 110 A1TR is shunted to close the back contact of the armature A1TR⁸⁶. It is to be noted in connection with westbound traffic that in the event the train moves into the siding *d*, that when the train has vacated the section 1T and the switch A1 115 is restored to its normal position the normal energizing circuit for the route locking relay 1-3LS is completed and that relay reenergized.

If a train wishes to advance east from the siding *d*, the setting of the switch A1 of the siding 120 moves the contact L21 to its reverse position and completes the energizing circuit to the signal controlling relay 2H to clear the signal 2 in the event no other train occupies a track section. As the train advances east from the siding *d*, the 125 operation of the stick relay 1S and the route locking relay 1-3LS will be the same as that pointed out in connection with the eastbound train advancing on the main track *a*.

I shall next assume that a northbound train 130 enters the track section A4T at a time when all the other track sections are unoccupied. The shunting of the track relay A4TR completes the circuit to the relay 4H and that relay is energized to clear the signal 4. As the relay 4H picks up 135 the circuit to the signal controlling relays of the opposing signal 5 is opened to prevent this signal from being cleared. The route locking circuit to the relay 4-5LS is opened at the front contact of armature A4TR⁹² as the northbound train enters the section A4T and then as the relay 4H picks up to open the back contact of armature 4H⁹⁰ the route locking relay 4-5LS is deenergized to lock out the signal controlling relays of the east and west road at the front contact of its armature 140 19. As the northbound train enters the section 4T the stick relay 4S is energized after which its stick circuits retain it energized until the northbound train vacates the section 4T and travels away from the crossing through the sections B5T and A5T. 145

When the northbound train has vacated these track sections the track relay 4TR and the repeater relay A5TP are reenergized to open the back contacts of armatures 109 and A5TP¹⁰, respectively, with the result that the stick relay 4S and the route locking relay 4-5LS are returned to their normal condition. The route locking relay 4-5LS will function to prevent the false clearing of a signal on the east and west road in 10 the same manner as the relay 1-3LS functioned in connection with east and westbound traffic. As relay 4S is picked up the front contact of the armature 4S⁹⁷ is closed and the first step of restoring the relay 4-5LS is accomplished, and 15 then when the relay A5TP is deenergized and armature A5TP⁹⁴ engages its back contact the second step is accomplished and relay 4-5LS is restored to its normal condition. That is to say, the restoring of the route locking relay 4-5LS 20 requires that the track section 4T first be shunted and then the subsequent shunting of the track section A5T.

Let us next assume that a southbound train enters the approach section A5T when no other train 25 occupies a track section. The deenergizing of the track repeater relay A5TP completes the circuit to the relay A5H and the signal A5 is cleared. As the relay A5TP is deenergized a circuit to the time element device 5TE is closed at armature 100 and 30 that relay started to function. However, if the southbound train proceeds on south it will be over the crossing 25 before the five minute time period required for the relay 5TE to operate has elapsed and thus under this traffic condition the time element device will have performed no useful function, 35 while the remaining apparatus will have functioned in a manner similar to that described for the other directions of traffic.

Let us now assume that this southbound train 40 enters the section A5T and the signal A5 is cleared, the route locking rendered effective and the energizing circuit for the time element device 5TE closed the same as mentioned above. The southbound train this time instead of proceeding over 45 the crossing 25 stops and does switching service in the vicinity of the siding c so that it is delayed for a period greater than the five minute interval required for the time element relay 5TE to operate its contacts. At the expiration of the predetermined period the time element relay 5TE 50 causes the armature 5TE⁵⁶ to disengage its back contact to open the circuit to the relay A5H and signal A5 is set at stop. The disengaging of armature 44 from its back contact prevents the relay 4H from becoming energized to clear the opposing signal 4 should a northbound train enter the section A4T. As the armature 5TE⁵⁷ engages its front contact the circuit to the relay B5H is closed and that relay is energized to clear the 55 special low speed signal B5 and, also, to retain the route locking circuit to the relay 4-5LS open at the armature 88.

If no train shows up on the east and west road, 60 then when the southbound train is ready to advance over the crossing it does so under the signal B5 and the apparatus functions as the southbound train passes over the crossing 25 and through the track section A4T the same as it does for a train not stopped to do switching. Let us 65 assume now that while the southbound train is switching and after the signal B5 has been cleared due to the fact that the predetermined time interval of the time element device 5TE has expired, a train enters either the approach section 70 A1T or A3T of the east and west road. This

train will cause the signal B5 to be set at stop and the preference taken away from the southbound train. If it is the section A1T that is entered the circuit to the relay B5H is opened at the front contact of armature A1TR⁶⁰. As the relay B5H drops an energizing circuit for the route locking relay 4-5LS is closed inasmuch as the time element relay 5TE has lifted the armature 107 into engagement with its front contact. This circuit can be traced from positive terminal 80 BL through the back contacts of armatures 88, 89 and 4H⁹⁰ of relays B5H, A5H, and 4H, respectively, wire 91, front contact of armature 107, wire 108, winding of relay 4-5LS and to the negative terminal CL. As the relay 4-5LS picks up, 90 the route locking is released and precedence is taken away from the southbound train. As soon as the route locking is released the circuit to the relay 1H is closed and the signal 1 cleared. From this point on the apparatus will function for the 95 eastbound train that has entered section A1T, the same as previously described. After this eastbound train has passed over the crossing 25 and vacated the section 1T a circuit is closed to the relay B5H that extends from positive terminal 100 BL up to the armature 5TE⁵⁷ as was pointed out above and then as armature 5TE⁵⁷ now engages its front contact the circuit extends through contact L⁵⁸, front contact of armature 1S⁶² of the stick relay 1S as that relay is closed by the eastbound train entering the section 1T, front contact of armature A1TR⁶⁰ and winding of relay B5H to the negative terminal CL. Thus the signal B5 is again cleared for the southbound train and the route locking relay 4-5LS is again de- 105 energized. As the eastbound train moves away from the crossing and vacates the section A3T the relay B5H is retained energized by the circuit through the front contacts of armatures A3TR⁵⁹ and A1TR⁶⁰ of track relays A3TR and A1TR, re- 115 spectively. If it is a westbound train that appears on the crossing road then the relay B5H is deenergized by the opening of the armature A3TR⁵⁹ and precedence is taken away from the southbound train and the signal 3 cleared for the 120 westbound train. As the westbound train advances over the crossing and vacates the section 1T the relay B5H is reenergized by the circuit through the armature A3TR⁵⁹ and the front contact of armature 3S⁶³ of the stick relay 3S, as 125 that relay is picked up by the westbound train entering section 1T.

When the southbound train has finished switching and advanced close enough to the signal 5 to occupy the short track section B5T, the relay 120 B5H is retained energized by the circuit through the front contact of armature 5TE⁵⁷ and the back contact of armature B5TR⁶¹ of the track relay B5TR. The southbound train now regains its precedence and the signal B5 is retained energized even though a train on the east and west road should now enter an approach track section. It is to be noted that as the southbound train vacates the section B5T and the track repeater relay A5TP is energized the circuit to the time element device 5TE is opened and its contacts immediately are restored to their original positions. It is also to be noted that the time element device 5TE cannot function for a northbound train even though that train should stop 140 to do switching at the siding c due to the fact that the stick relay 4S is picked up as the northbound train entered the section 4T and thus the circuit to the relay 5TE is held open at the armature 145 102.

The manually controlled time releases b^4 and a^3 will be located near the crossing 25 and may take any one of the many forms well-known in the art, for example, they may be of the clock-
5 work type. The manually controlled time release provided for each road permits the release of the crossing in the event of a track circuit failure in connection with any one of the track sections. A failure of the track section A1T would

- 10 cause signal 1 to be cleared and the route locking relay 1-3LS deenergized. If now a northbound train desires to proceed over the crossing a member of the crew will operate the release a^3 . The operation of the release a^3 first opens the circuits 15 to all the signal controlling relays at the contacts 18 and 38 and then as the contact 34 closes, the route locking circuit to the relay 1-3LS is closed and that relay is then retained energized by its stick circuit. As the time release a^3 returns to its 20 normal position at the end of this movement the contact 38 is made to close slightly ahead of the contact 18 so that the relay 4H will be energized and the signal 4 cleared before the circuit is restored to the signal controlling relays for the 25 east and west road at the contact 18. When relay 4H is energized and the signal 4 cleared the northbound train can then proceed over the crossing 25 in the usual manner. The manually controlled time release b^4 operates to release the crossing for east and westbound trains where 30 there is a failure of an approach track section of the north and south road in a manner similar to that just described for the release a^3 . In connection with the contacts 17 and 37, the contact 17 35 will be so adjusted as to close slightly ahead of the contact 37 as the time release b^4 returns to its normal position at the end of an operation. With contact 17 closing ahead of contact 37 then the circuit to the signal controlling relays for the 40 east and west road will be closed and these relays function before the circuit to the relays for the north and south road is closed.

Therefore, the system here disclosed provides an automatic interlocking wherein the approach 45 of a train causes a signal to be cleared for the traffic route to be traversed by that train only when no converging route has previously been established. As the train approaches on the established route the signals of all converging or 50 intersecting routes are locked out by a route locking circuit. To release this route locking circuit requires two subsequent steps. These two steps are accomplished as the train shunts two successive track sections and thus the route locking 55 cannot be released and a signal cleared for an intersecting route as the result of a momentary shunting of a track circuit. This system obtains the same route locking protection for movements 60 from a passing siding that ends within the interlocking limits as is given to traffic on the main track. Where a train is held for switching, or for other purposes, within the vicinity of the interlocking after the route has been established 65 for that train an automatic time element device cancels the preference established for the train and displays a special low speed signal which can also be cancelled and an intersecting route set up in response to the approach of a train on the 70 opposing road. As soon as the train on the opposing road has proceeded over the intersection the special low speed signal for the first train is again displayed. Precedence for the switching train is fully reestablished whenever that train 75 enters a preliminary short track section showing

thereby that it is ready to advance over the intersection.

Manually controlled time releases located in the vicinity of the crossing permit release of the crossing in the event of a track circuit failure of one of the approach track sections, and preference is established for the road that desires to use the crossing.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a traffic route, a first signal to govern traffic over the route under certain traffic conditions, a first normally deenergized relay to control said signal, a second signal to govern traffic over the route under certain other traffic conditions, a second normally deenergized relay to control said second signal, a normally inactive time element device adapted to function in a predetermined time interval after its energizing circuit is closed, a track circuit means responsive to a train approaching said route to energize the first relay to clear the first signal and to close the energizing circuit of said time element device, and means controlled by said time element device to deenergize the said first relay and to energize the second relay to clear the second signal at the expiration of said predetermined time interval.

2. In combination, a traffic route, a first signal normally at stop to govern traffic over the route under certain traffic conditions, a second signal normally at stop to govern traffic over the route under other traffic conditions, a normally inactive time element device adapted when energized to function in a predetermined time interval, an approach track section, means responsive to a train occupying said track section to clear said first signal and to energize said time element device, and means controlled by the time element device to set the first signal at stop and to clear the second signal at the expiration of said predetermined time interval.

3. In combination, two intersecting railroads, an approach track section and a crossing track section for each railroad, a signal for each railroad to govern traffic through its crossing track section and each cleared when a train enters its approach track section, a normally inactive time element device associated with one of said railroads and adapted when active to operate in a predetermined time interval, means responsive to a train entering the approach track section of the railroad with which said time element device is associated to render active the time element device and to prevent the clearing of the signal for the other road, means controlled by the said time element device to set the signal for its own road at stop and to cancel the control over the signal of the other road at the expiration of the predetermined time interval when the train in the approach track section has been delayed for a period greater than the said time interval, and a second signal for the road with which said time element device is associated to govern the delayed train through the crossing track section of that road.

4. In combination, a first, a second and a third track section for a railway forming a traffic route, a second railway intersecting the second track.

section of the first railway, a route locking circuit so controlled as to prevent a train on the second railway from proceeding over the intersection when a train occupies the first track section, a stick relay energized as the train in the first section advances into the second track section, a track relay controlled by the third track section and a circuit means controlled jointly by said stick relay and said track relay to release the route locking circuit.

5. In combination, two intersecting railway tracks, an approach track section for each railway, a route locking circuit for each railway track so controlled as to prevent a train on the opposite track from proceeding over the intersection when a train occupies the approach track section of the track with which said route locking circuit is associated, and circuit means to release a given one of the route locking circuits 20 when two trains one on each railway enter the approach track sections simultaneously.

6. In combination, two intersecting railway tracks, an approach track section for each railway, a normally energized route locking circuit for each railway, means to deenergize a route locking circuit to prevent a train on the opposite track from proceeding over the intersection when a train enters the approach track section of the track with which the route locking circuit is associated, and means controlled by a given one of said route locking circuits to release the other route locking circuit when both route locking circuits are simultaneously deenergized.

7. In combination, a first and a second track section for a railway track, a second railway track intersecting the second track section, a siding track converging into the said second track section, a normally energized route locking circuit for the first mentioned railway track arranged when deenergized to prevent a train on the second mentioned railway track from proceeding over the intersection, and circuit means to deenergize said route locking circuit when a train on the first railway track enters the first section or when the siding switch is set for traffic to move from the siding to the second track section.

8. In combination, a stretch of railway, a first and a second approach track section to said stretch, an A signal and a B signal to govern traffic through said stretch, a second railway intersecting said stretch, a normally energized route locking relay for said stretch, means responsive to a train entering the first approach track section to clear the A signal and to deenergize the route locking relay to prevent a train on the second railway from proceeding over the intersection, a time element device to set the A signal at stop, to reenergize the route locking relay and to clear the B signal when the train has been delayed in the first approach track section a predetermined period of time, and means to deenergize the route locking relay when the train enters the second approach track section.

9. In combination, a stretch of railway, a first and a second approach track section to said stretch, an A signal and a B signal to govern traffic through the stretch, a second railway intersecting the stretch, an approach track section for said second railway, a signal for said second railway to govern traffic over the intersection, a normally energized approach locking relay for the stretch, means responsive to a train entering the first approach track section to clear the A signal and to deenergize the route locking relay to prevent the signal on the second railway

from being cleared; a time element device to set the A signal at stop, to clear the B signal and to reenergize the route locking relay when the train in the first approach section is delayed a predetermined period of time; means responsive to a train entering the approach section of the second railway to set the B signal at stop and to clear the signal on said second railway, and means to hold the B signal at clear and to deenergize the route locking relay when the first mentioned train enters the second approach track section.

10. In combination, a railway having a crossing track section and an approach track section on each side of said crossing track section, a second railway intersecting said crossing track section, a track circuit for each track section, a signal at each end of said crossing section to govern traffic in opposite directions through said section, a normally energized route locking relay associated with the crossing section adapted when deenergized to prevent a train on the second railway from proceeding over the intersection, means controlled by the track circuit of each approach section to clear the signal adjacent the section and to deenergize the route locking relay when a train occupies the approach section, a stick relay for each signal, means to energize a stick relay as a train advances past the associated signal into the crossing track section, stick circuits to retain said relay energized while the train occupies the crossing section and the opposing approach section, a contact of an energizing circuit for the route locking relay closed when the stick relay is energized, and circuit means controlled by the stick relay when energized to prevent the opposing signal from clearing as the train occupies the opposing approach track section.

11. In combination, two intersecting railways, a signal for each railway to govern traffic over the intersection, a signal controlling circuit for each signal, an approach track section for each railway adapted to clear the associated signal to advance a train over the intersection as a train enters that section, a route locking circuit for each railway so controlled as to prevent the signal of the opposing railway being cleared when the associated approach track section is occupied, a manually operated time release for each railway each arranged that when operated it first opens the signal controlling circuits, then closes the route locking circuit of the opposing railway and then recloses the signal controlling circuits with the circuit for the signal of the associated railway closed slightly ahead of the circuit for the signal of the opposing railway and thereby give precedence to traffic on the associated railway.

12. In combination, two intersecting railway tracks, a siding for one of said railways adjacent the intersection of said railway tracks and provided with a switch, a normally energized route locking circuit for the railway having the siding, a signal to govern traffic from the siding over the intersection normally at stop, a relay energized when the switch is set for the siding to clear said signal and to deenergize said route locking circuit, means controlled by the switch to retain said route locking circuit deenergized as long as it remains set for the siding, and means controlled by the route locking circuit arranged to prevent a train on the other railway from advancing past the intersection when said circuit is deenergized.

HENRY S. YOUNG. 150
